Des. 224,500
Patented Aug. 1, 1972

224,500

SHEET OR SIMILAR ARTICLE OF BED LINEN

Nancy Ann Scherer, Plainfield, N.J., assignor to Cannon
Mills Company, Kannapolis, N.C.

Filed Feb. 16, 1971, Ser. No. 115,935

Term of patent 14 years

Int. Cl. D6—13

U.S. Cl. D6—264

FIG-2

FIG. 1 is a top plan view of a sheet or similar article of bed linen showing my new design, a design unit being marked off with dash lines, which unit is repeated in regular succession beyond the unit boundaries; and

FIG. 2 is an enlarged top plan view of the design unit shown within the dash lines on FIG. 1.

I claim:

The ornamental design for sheet or similar article of bed linen, substantially as shown and described.
